UNITED STATES PATENT OFFICE.

FRANZ ESCHENBACH, OF ST. JAMES, NEW YORK.

ICE-CUTTING MACHINE.

995,236.

Specification of Letters Patent. Patented June 13, 1911.

Application filed June 10, 1910. Serial No. 566,168.

To all whom it may concern:

Be it known that I, FRANZ ESCHENBACH, a citizen of the United States of America, residing in St. James, in the county of Suffolk and State of New York, have invented certain new and useful Improvements in Ice-Cutting Machines, of which the following is a specification.

This invention relates to an improved machine for cutting ice.

The object of this invention is to supply a machine for cutting through the entire thickness of the ice in two parallel lines which are distant from each other the length of the blocks into which the ice is to be cut; and for this purpose the invention consists of an ice-sawing machine comprising front-wheels having a ribbed circumference, a sled pivotally connected by upwardly-curved arms with the front-axle, said sled being formed of horizontal bars and transversely connected runners, a transverse shaft supported in bearings on the horizontal bars, rotary circular saws near the ends of said shaft, handles at the rear-end of the horizontal bars, a chain and sprocket-wheel connection between one of the front-wheels and the saw-shaft, and means for adjusting the horizontal bars higher or lower toward the runners, according to the thickness of the ice, and transverse guard-frames extending across the sled in front of and at the rear of the circular saws, as will be fully described hereinafter and finally pointed out in the claims.

In the accompanying drawing, Figure 1 represents a side-elevation of my improved machine for sawing ice into blocks, and Fig. 2 is a plan-view of the same.

Similar letters of reference indicate corresponding parts.

Referring to the drawing, *a* represents the front-axle of my improved machine for sawing ice. To the axle is applied a shaft *s* for hitching up two horses by which the necessary power is furnished to the sawing machine. The tires of one or both front-wheels *b* are provided with transverse ribs *b*¹ that have a slight inclination so as to bite into the surface of the ice when the machine is drawn over the ice-covered surface of a river, lake, or other body of water. To the front-axle are applied two curved hanger-arms *d* by means of eyes *d*¹ so as to form a pivotal connection with the front-axle, as

shown clearly in Fig. 2. To the rear-ends of the curved arms *d* are attached horizontal bars *e* which are connected at their rear-ends with handles *e*¹ and a transverse board *e*². Below the parallel bars *e* are arranged parallel runners *r*, preferably in line with the front-wheels, which are connected by transverse front and rear-braces *r*¹ and transverse and slightly inclined guard-frames *f* that are rigidly attached to the runners *r* and provided with recesses *f*¹ for the horizontal bars *e*. To the bars *e* are attached journal-blocks *g*¹ which support a transverse rotary shaft *g* on which two circular saws *g*², one near each end, are mounted. The shaft *g* and the circular saws *g*² are rotated in the direction of the arrow by a sprocket-wheel *h* on one of the front-wheels *b*, a sprocket-chain *h*¹, and a sprocket-wheel *h*² on the saw-shaft *g*. When the machine is drawn over the ice, the sled is held on the surface of the ice by the attendant taking hold of the handles *e*¹ and the sled and saws are pressed in downward direction, so that the latter can cut into the ice and form saw-cuts through the entire thickness of the same. For raising or lowering the saws, so as to cut through ice of different thicknesses upright screw-posts *i* are secured by countersunk heads to the transverse brace-rods between the runners, passed through holes in the horizontal bars *e*, and attached thereto by nuts *i*¹ above and below the bars, as shown in Fig. 1. For thicker ice the bars *e* have to be lowered on the screw-posts toward the runners, while for cutting thinner ice they have to be raised away from the runners, so that the saws cut to greater or lesser depth as required.

If desired, for increasing the pressure on the saws, a weight may be placed on the transverse board *e*² so that an additional pressure is exerted thereon independently of the pressure exerted by the attendant on the handles of the bars *e*, or in place of the weight the attendant may stand on the board *e*², in which case he holds on to the rear guard-frame *f*. The guard-frames *f* are arranged at the front and rear of the saws so as to prevent accidents by the same. The seat of the driver may be arranged on the front-axle in the same manner as in agricultural machines.

By the machine a field of ice can be cut up in a very short time so as to be broken

up into blocks, which are then run into the ice-houses by means of conveyers in the usual manner.

Having thus described my invention, I claim as new and desire to secure by Letters Patent:

1. An ice-cutting machine comprising a front axle, wheels on said axle supporting the machine on the ice, arms secured to said 10 axle and extending downwardly and rearwardly, horizontal bars spaced from the ice and secured at their front ends to said arms and having holes near their ends, parallel 15 runners below said arms, cross braces connecting said runners, upstanding screw-posts on said braces and passing through said holes, nuts on said posts above and below the bars for adjusting the height of said bars, a transverse rotating shaft carried by 20 said bars, saws on said shaft, means for communicating motion from one of the wheels to the shaft.

2. An ice-cutting machine, comprising a front axle, wheels on said front axle for 25 supporting the machine on the ice, a shaft secured to said axle for drawing the machine, rearwardly and downwardly extending arms secured at the front ends to said axle and extending to a point to the rear 30 of the wheels and a distance above the ice, approximately horizontal bars secured to the rear ends of said arms and formed into handles at their rear ends and provided with vertical holes near both ends, parallel 35 runners, transverse braces connecting said runners, screw-posts upstanding on said transverse braces and passing through said holes in the horizontal bars, nuts on said posts above and below the bars for adjusting the height of the bars above the ice, journal 40 blocks secured to the lower face of the horizontal bars about midway between the screw-posts, a transverse rotary shaft carried in said journal blocks, circular saws provided at each end of the rotary shaft outside of the horizontal bars, a sprocket wheel on one end of the rotary shaft, a sprocket wheel on one of the wheels, a horizontal transverse board connecting the rear 45 ends of the horizontal bars, slightly inclined guard frames attached to both ends of said runners and provided with recesses for the horizontal bars, said saws being between the 50 runners.

at each end of the rotary shaft outside of 45 the horizontal bars, a sprocket wheel on one end of the rotary shaft, a sprocket wheel on one of the wheels, and a sprocket chain connecting the sprocket-wheels.

3. An ice-cutting machine, comprising a 50 front axle, wheels on said front axle for supporting the machine on the ice, a shaft secured to said axle for drawing the machine, rearwardly and downwardly extending arms secured at the front ends to said 55 axle and extending to a point to the rear of the wheels and a distance above the ice, approximately horizontal bars secured to the rear ends of said arms and formed into handles at their rear ends and provided with 60 vertical holes near both ends, parallel runners, transverse braces connecting said runners, screw-posts upstanding on said transverse braces and passing through said holes in the horizontal bars, nuts on said posts 65 above and below the bars adjusting the height of the bars above the ice, journal blocks secured to the lower face of the horizontal bars about midway between the 70 screw-posts, a transverse rotary shaft carried in said journal blocks, circular saws provided at each end of the rotary shaft outside of the horizontal bars, a sprocket wheel on one end of the rotary shaft, a sprocket wheel on one of the wheels, a horizontal transverse board connecting the rear 75 ends of the horizontal bars, slightly inclined guard frames attached to both ends of said runners and provided with recesses for the horizontal bars, said saws being between the 80 runners.

In testimony, that I claim the foregoing as my invention, I have signed my name in presence of two subscribing witnesses.

FRANZ ESCHENBACH.
